UNITED STATES PATENT OFFICE

DAVIS E. SMITH, OF DETROIT, MICHIGAN

PISTON

Application filed July 9, 1927. Serial No. 204,531.

The present invention pertains to a novel piston of the trunk type adapted for use particularly in internal combustion engines where a high temperature is established in 5 the cylinders.

The principal object of the invention is to provide a piston of this character constructed of aluminum alloy or other material having a high co-efficient of expansion and wherein there is provided a means 10 for reducing the expansion of such material.

The expansion of aluminum alloy pistons used in common practice is much greater than the expansion of the cylinder and the 15 pistons are consequently fitted with sufficient clearance to accommodate the piston expansion under the highest temperature in the cylinder. This clearance is, however, detrimental before the cylinder reaches 20 its maximum temperature which is necessary in order that the piston may properly fit the cylinder. Consequently, while the cylinder is cool, the operation is impeded by piston slap, disagreeable noise, excessive 25 wear on the piston and cylinder walls, and leakage of oil past the piston rings.

The present invention overcomes these difficulties by the provision of an insert of low thermal expansion material in the wall 30 of the piston body so that the expansion of the latter is limited.

The invention is fully disclosed by way 35 of example in the following description and in the accompanying drawings, in which

Figure 1 is a longitudinal section of the device, partly in elevation;

Fig. 2 is a longitudinal section on the line II-II of Fig. 1;

Fig. 3 is an elevation of the tubular insert, and

Fig. 4 is a sectional view of a modified construction.

Reference to these views will now be made by use of like characters which are 45 employed to designate corresponding parts throughout.

The piston illustrated in the several figures includes a head 1 and a skirt 2 between which is formed a transverse bearing 3.

50 The bearing is joined to the head by means

of ribs 4 at the ends of the bearing. These parts are made of aluminum, and in ordinary practice must be considerably smaller than the cylinder at low temperature in order that their excessive expansion at high 55 temperature may be accommodated in the cylinder. This principle of construction is the cause of numerous defects already described. In order to avoid such detrimental clearance between the cylinder wall and piston at low temperature, I form the piston of such size as to fit the cylinder reasonably well even at low temperature, and then provide the piston with an inner member of a low co-efficient of expansion in order to 60 prevent excessive expansion of the piston at 65 the higher cylinder temperatures.

This insert consists of a tube 6 formed preferably of nickel steel. It is embedded in the walls of the head and skirt as indicated by numerals 7 and 8 respectively, and extends circumferentially of these parts in order to retain the same at all points. The insert may be positioned during the casting of the head and skirt, and with this object 75 in view it is formed with perforations 9 which afford better adhesion of the alloy thereto. Also, the insert is formed with larger openings 10 which align with the ends of the bearing 3. In case the skirt 2 has 80 a diameter greater than the length of the bearing 3, the insert is flared as at 11 from the bearing to the skirt.

It is desirable to avoid excessive expansion particularly in the skirt, and the construction may accordingly be simplified as 85 illustrated in Figure 4. In this case the insert is merely a ring or band 12 embedded in the skirt 2' without extending upwardly 90 into the head of the piston.

As already stated, the piston is dimensioned to run fairly well in the cylinder even at low temperatures. The natural high expansion of the aluminum alloy at higher 95 temperatures is restrained by the steel insert 6 which has a comparatively low co-efficient of expansion. The result of this construction is a device having the advantage of an aluminum alloy piston without the 100

attendant difficulties of clearance and high expansion of the material.

Although a specific embodiment of the invention has been illustrated, and described, it will be understood that various alterations in the details of construction may be made without departing from the scope of the invention as indicated by the appended claim.

10 What I claim is:—

10 In a piston of high thermal expansion material having a head and a separate skirt, a separate tubular member of low expansion material inserted circumferentially in the 15 wall of said head and skirt and forming a connecting means therebetween.

In testimony whereof I affix my signature.

DAVIS E. SMITH.
